UNITED STATES PATENT OFFICE.

EDWARD C. WARREN, OF CHICAGO, ILLINOIS.

ROTARY ENGINE.

SPECIFICATION forming part of Letters Patent No. 680,510, dated August 13, 1901.

Application filed January 31, 1900. Renewed February 5, 1901. Serial No. 46,154. (No model.)

To all whom it may concern:

Be it known that I, EDWARD C. WARREN, a citizen of the United States, residing at Chicago, in the county of Cook and State of Illinois, have invented a certain new and useful Improvement in Rotary Engines, of which the following is a specification.

The objects of my invention are to provide a relatively simple, compact, and highly efficient rotary engine; to avoid the use of cams, eccentrics, crank-arms, and all similar devices which tend to limit the speed of a rotary engine and also to dispense with the use of packing; to balance the pressure on all rotating parts, so as to secure a minimum of friction and avoid unevenness of wear, and also to balance the pressure on the reversing-valves; to provide a system of ports, valves, and operating means for quickly and easily reversing the engine; to provide an improved arrangement of ports, pistons, and abutments, and to thereby avoid dead-centers; to provide a practical and efficient form of compound double-expansion engine; to provide an improved and novel arrangement whereby full boiler-pressure may be admitted directly to the low-pressure cylinder, and to provide certain details of construction tending to increase the general efficiency of this type of engine.

To the attainment of the foregoing and other useful ends, my invention consists in matters hereinafter set forth and described.

In the accompanying drawings, Figure 1 is a perspective of a compound double-expansion rotary engine embodying my invention. Fig. 2 is a vertical, central, and longitudinal section of the same. Fig. 3 is a horizontal central section. Fig. 4 is a transverse section through the high-pressure cylinder on line $x x$ in Fig. 3. Fig. 5 is a similar section through the intermediate-pressure cylinder on line $y y$ in Fig. 3. Fig. 6 is a transverse section through the low-pressure cylinder on line $z z$ in Fig. 3. Fig. 7 is a longitudinal section through one of the two reversing-valve chambers mounted upon the high and low pressure cylinder casing, the said section being taken on line $x' x'$ in Fig. 4. Fig. 8 is a similar section of the other of the said valve-chambers, taken on a line $x^3 x^3$ in Fig. 4. Fig. 9 is a longitudinal section through one of the

two reversing-valve chambers mounted upon the low-pressure-cylinder casing, such section being taken on line $y' y'$ in Fig. 6. Fig. 55 10 is a similar section through the other of the said two reversing-valve chambers on line $y^2 y^2$ in Fig. 6. Fig. 11 is a view of one of the flat horseshoe-shaped rings which are arranged upon the abutment-shafts. 60

The engine which I have illustrated and described comprises three cylinders or piston-chambers and a like number of inclosed pistons. Steam is primarily admitted to the first or high-pressure chamber, exhausted 65 from the high-pressure cylinder into the second or intermediate-pressure cylinder, and from the latter exhausted into the third or low-pressure cylinder. In the first or high-pressure cylinder the piston is at all times 70 subjected to full boiler-pressure, and for this reason the engine may be properly termed a "compound double-expansion rotary engine."

In constructing an engine of the foregoing 75 description I first provide a base or bed A, adapted to afford a suitable support for the two cylinder-casings B and C. Separate casings may be provided for the three cylinders or piston-chambers, if so desired; but as a 80 matter of further improvement the casing B is adapted to afford high and intermediate pressure cylinders or piston-chambers, while the casing C is constructed to provide a low-pressure cylinder or piston-chamber. The 85 casings may be cast and properly bored to receive the pistons and may be provided with suitable heads or end plates $b b'$ and $c c'$. The casing B is, as previously stated, adapted to afford high and intermediate pressure piston-chambers, and to such end the inclosed piston D is provided with a peripheral flange d , which serves to divide the interior of the casing into two annular compartments or piston-chambers. (See Figs. 2 and 3.) The cylindrical piston D is also preferably provided with a couple of end flanges d' and d^2 , and the intervening spaces E and F between the latter and the flange d form, respectively, the high and intermediate pressure cylinders or piston-chambers. The rotary piston D is keyed to the shaft G, the latter being supported for rotation in suitable bearings a , a' , and a^2 and the heads or end plates $b b'$ being pro-

vided with stuffing-boxes $b^2 b^3$, through which extends the shaft G to prevent leakage. Peripheral projections d^8, d^4, d^5 , and d^6 are also formed upon the piston D in such manner as 5 to divide the annular piston-chamber E into four compartments, and like projections d^7, d^9 , and d^{10} serve to similarly divide the annular piston-chamber F. (See Figs. 4 and 5.)

Arranged at either side of the shaft D and 10 preferably in the same plane as the latter are a couple of shafts H and I. The said shafts are supported, respectively, in bearings $a^8 a^4$ and $a^5 a^6$, and the heads or end plates b and b' are preferably provided with stuffing-boxes 15 $b^4 b^5$ and $b^6 b^7$, through which the shafts H and I, respectively, extend.

Keyed to the shaft H, so as to rotate therewith, are a couple of cylindric abutments h and h' , and similarly mounted upon the shaft 20 I are a couple of like abutments i and i' . The abutments h and i are so arranged that their peripheries extend within the annular piston-chamber E and make contact with that portion of the outer surface of the piston D which 25 is included between the flanges d' and d . In this way the said abutments h and i are adapted to form a backing for the steam-pressure exerted in piston-chamber E, and in order to permit the piston projections d^8, d^4, d^5 , and 30 d^6 to pass the abutments the latter are provided, respectively, with recesses 11 and 22. The rotary abutments h' and i' are similarly arranged with reference to the annular piston-chamber F, and in order to permit the 35 piston projections d^7, d^9, d^8 , and d^{10} to pass the said abutments the latter are provided with recesses 33 and 44.

Arranged loosely upon the shaft II are three flat horseshoe-shaped rings h^2, h^3 , and h^4 , and 40 mounted likewise upon the shaft I are three similar rings i^2, i^3 , and i^4 . The middle ones of said rings serve to divide the abutment-chambers into two compartments and may be regarded practically as continuations of the 45 piston-flange d , the rings being of the same thickness as the said flange and arranged opposite the latter, as shown in Fig. 3. The other rings serve as end walls for the abutment-chambers, are arranged opposite the 50 flanges d' and d^2 , and may be regarded as continuations of the latter, it being observed that the said flanges form the outside end walls of the two piston-chambers and that each abutment fits and revolves snugly between a couple of piston-flanges and a couple of horseshoe-shaped rings. Each ring is provided 55 with a marginal recess or notch, which conforms to the periphery of the piston-flange and which gives the ring the aforesaid horseshoe-shaped form or appearance. (See Fig. 11.) The rings may, if so desired, be formed 60 integral with the casing—that is, the middle one integral with the casing B and the end ones integral with the heads b and b' —but as 65 a matter of improved and advantageous construction I prefer to adopt the arrangement shown and described, for with the rings made

integral with the casing some difficulty would be experienced in assembling the different parts of the engine, as in such case the abutments would have to be first placed in their respective positions and the abutment-shafts then slipped through and the abutments keyed, whereas with the construction shown the rings and abutments may all first be 70 properly mounted upon the shaft and the whole then placed in position within the casing without difficulty.

As a means for balancing the pressure of the steam upon the rings and abutments and 75 as a means for keeping the latter in contact with the pistons, or, in other words, as a means for counteracting the pressure exerted upon the abutments by the steam in the piston-chambers, the casing is preferably formed 80 with pressure spaces or cavities b^8 and b^9 . The said spaces or cavities are arranged back of the abutments, and the steam carried from the piston-chambers by the abutment-recesses serves to maintain in such cavities or 85 spaces the desired degree of pressure. As the piston projections in the high-pressure piston-chamber preferably alternate with the piston projections in the intermediate-pressure piston-chamber, the recesses in the abutments allotted to the said two chambers are 90 also preferably arranged to alternate. The piston projections operating, respectively, within the high and intermediate pressure chambers are preferably four in number in 95 each case, while the recesses with which each rotary abutment is provided are preferably two in number. For every rotation, therefore, of the rotary piston D it is obvious that 100 the rotary abutments must revolve twice, and to this end the gears U, V, and W, by which 105 the shafts G, H, and I are connected, are so proportioned relatively as to obtain a speed of rotation on the part of the shafts II and I exactly double that which may be imparted 110 to the shaft G. By such arrangement there will be little or no friction between the piston and abutments, as the latter have simply a 115 rolling contact with the former, and while the number of piston projections and co-operating abutment-recesses may be varied, as desired, I prefer the arrangement and number described and illustrated.

Steam is admitted primarily to the high-pressure cylinder or piston-chamber by way of an 120 inlet-pipe J, exhausted from the high-pressure chamber into the intermediate-pressure chamber and from the latter then exhausted into the low-pressure cylinder by way of a pipe K. For the purpose of reversing the engine I 125 have provided suitable piston-valves, which are arranged for reciprocation within suitable valve-chambers formed in the casings B and C. The two piston-valves L and M, which control the admission and exhaust ports leading to and from the high and intermediate pressure chambers, are arranged for reciprocation, respectively, within the valve-chambers $b^{10} b^{11}$, which latter are preferably bored 130

or suitably formed within the cylinder-casing B. The piston-valve L, as illustrated, comprises a piston rod or stem l and three disks or piston-heads l', l'', and l'', mounted upon the rod or stem and fitted to slide within the valve-chamber b¹⁰. The valve M is similar in form and construction to the valve L and consists of a piston-rod m and three disks or heads m', m'', and m''. Each valve-chamber may be provided with heads adapted to be screwed into the casing, and the piston-rods may be arranged to extend and work through stuffing-boxes of any suitable construction. (See Figs. 7 and 8.)

Referring now to Figs. 4, 5, 7, and 8, steam will pass from the inlet-pipe J into a duct or passage 5, which latter extends transversely across and through the upper portion of the casing B. The ends of the said duct or passage 5 communicate with the valve-chambers b¹⁰ and b¹¹. With the valves in the position shown in Figs. 7 and 8 steam will pass from the duct 5 into the space between the disks l'' and l''' in the chamber b¹⁰ and also into the space between disks m'' and m''' in the chamber b¹¹. From valve-chamber b¹⁰ steam will enter the annular piston-chamber E by way of port 6 and by exerting pressure upon the piston projection d³ drive the piston D in the direction indicated by the arrow. At the same time, however, steam will pass from the valve-chamber b¹¹ by way of port 7 and entering the piston-chamber E contribute to the rotary movement of the piston by exerting pressure upon the piston projection d⁵. By thus permitting steam to enter the piston-chamber at opposite points the pressure upon the outer surface of the piston will be balanced, thereby preventing unevenness of wear and reducing the friction of the shafts or journals revolving in their bearings to a minimum. With the piston rotating in this direction the exhaust from the chamber E will take place through ducts 8 and 9.

Referring to Figs. 4, 5, 7, and 8, it will be seen that exhaust-steam is entering the port or duct 8 from between the piston projections d⁴ d⁵, and also that exhaust-steam is entering port or duct 9 from between piston projections d³ d⁶. The steam which enters duct 8 will pass into the space between disks l' l'' in valve-chamber b¹⁰, while at the same time steam from duct 9 will enter space between disks m' m'' in valve-chamber b¹¹. From the space between the two disks l' l'' in valve-chamber b¹⁰ the exhaust-steam from the high-pressure chamber will pass into piston-chamber F by way of duct 10, while from the space between the two disks m' m'' in valve-chamber b¹¹ exhaust-steam will enter piston-chamber F by way of the port or duct 11. The piston-chamber F is, it will be observed, substantially three times the size of chamber E, and the piston projections in the former presented, therefore, substantially three times the pressure-surface presented by the piston projections in the latter. Such being the case,

steam passing from between the piston projections d⁴ d⁵ in the high-pressure chamber will be free to expand between piston projection d⁷ and abutment h' in the intermediate-pressure chamber, and at the same time steam from between piston projections d³ d⁶ will be permitted to enter and expand between piston projection d¹⁰ and abutment i'. The steam carried around between piston projections d⁹ and d¹⁰ will exhaust into the port or duct 12, while steam carried between piston projections d⁷ d⁸ will exhaust into duct 13. Extending across and through the upper portion of the casing B is a duct or passage 14, which communicates at each end with the valve-chambers b¹⁰ and b¹¹. Steam entering the space between disk l' and the end wall of valve-chamber b¹⁰ will escape therefrom by way of said duct 14 and from the latter will then enter the pipe K, which leads to the low-pressure cylinder. In a similar manner, entering the space between disk m' and the end wall of valve-chamber b¹¹, it will pass into duct 14, and from the latter will also be conveyed by way of pipe K to the low-pressure cylinder. The longitudinal ducts or passages 15 and 16, which extend, respectively, above the two valve-chambers b¹⁰ and b¹¹, serve not only to balance the reversing-valves, but also as mediums of communication between the high and intermediate pressure chambers when the reversing-valves are shifted for the purpose of reversing the engine. Assuming that the said valves have been shifted to the opposite ends of their respective chambers, it will be seen that steam will then pass from the duct 5 into and between the disks l' l'' and from such space into the piston-chamber E by way of duct 8. Also in such case steam will enter the space between the disks m' m'' in chamber b¹¹ and from the latter pass into the piston-chamber E by way of duct 9. The rotary piston by such admission of steam will be rotated in the opposite direction, and the exhaust from the high-pressure chamber will then take place through ducts 6 and 7. Exhaust-steam admitted to duct 6 will pass into the space between disk l'' and the end wall of valve-chamber b¹⁰, while in a similar manner steam will enter the space between disk m'' and the end wall of valve-chamber b¹¹. From the said space between the disk l'' and the end wall of chamber b¹⁰ steam will then pass into duct 15 and be admitted to chamber F by way of duct 12, it being understood at this juncture that sufficient space exists between the disk l' and the end wall of the valve-chamber to insure and establish communication between the ducts 15 and 12. Steam admitted to the space between the disk m'' and the end wall of chamber b¹¹ will enter the intermediate-pressure chamber by way of ducts 16 and 13, and the exhaust therefrom will then take place through ducts 10 and 11. Such exhaust passing from duct 10 into and between the disks l' l'' will escape into pipe K by way of duct 14, and the exhaust received

between the disks m' m^2 by way of duct 11 will escape in a like manner by way of duct 14. Referring now to Figs. 2, 3, 6, 9, and 10, the low-pressure portion of the engine comprises a casing, piston, and abutments somewhat similar in form and construction to the high and intermediate pressure portion, but relatively large and involving practically but one piston-chamber. The casing C, which is adapted to afford a suitable piston-chamber for the piston N, may be provided, as previously stated, with heads c c' and also with stuffing-boxes c^2 c^3 , through which extends the shaft G. The said piston N is cylindric in form and provided with peripheral flanges n , n' , and n^2 . The latter are arranged so as to divide the interior of the casing into annular compartments, and the piston projections of one compartment or chamber preferably coincide with those of the other compartment. Arranged at each side of the piston N and preferably in the same plane as the shaft G are a couple of shafts Q and P. The said shafts are supported for rotation in bearings a^7 a^8 and a^9 a^{10} , respectively, and each shaft is arranged to extend through suitable stuffing-boxes c^4 c^5 and c^6 c^7 . Keyed to shaft O are a couple of cylindric abutments o and o' , and similarly mounted upon the shaft P are a couple of similar abutments p and p' . The said abutments extend within the piston-chambers, so as to make contact with the piston N, and are similar in function and operation to the abutments previously described. The abutments o and p are provided, respectively, with notches or recesses 17 17 and 18 18, so as to permit the piston projections n^3 , n^4 , n^5 , and n^6 to pass, and the abutments o' and p' are provided, respectively, with similar notches 19 19 and 20 20, with reference to the continuation of such piston projections on the other side of the flange n' . The said abutments, like those of the high and intermediate pressure chambers, are preferably arranged to make two revolutions to one on the part of the rotary piston, and to this end the gears X, Y, and Z, which connect the shafts O, P, and G, are so proportioned relatively that for each revolution given the latter two revolutions will thereby be given the former. In this way a rolling contact is secured between the abutments and piston and friction reduced to a minimum. A couple of steam-spaces c^8 c^9 are also formed within the casing C, the steam-space c^8 being located back of the abutments o and o' and the steam-space c^9 being located at the opposite side of the engine and back of the abutments p and p' . The steam carried from the piston-chambers by the recesses in the several abutments serves to maintain a constant pressure in the said steam-spaces and in such way to keep the abutments in contact with the piston. Three flat horseshoe-shaped rings o^2 , o^3 , and o^4 are loosely mounted upon the shaft O, and three similar rings are arranged upon the shaft P.

The said rings are similar in form and function to the rings previously described in connection with the high and intermediate pressure portions of the engine and for this reason do not require further description.

Exhaust-steam from the intermediate-pressure chamber is primarily admitted to the low-pressure chamber by way of pipe R and 75 is ultimately exhausted from such chamber by way of an outlet-pipe Q. The ports or ducts by which steam is admitted to and exhausted from the low-pressure piston-chamber are preferably controlled by a couple of 80 reversing-valves R and S, similar to the valves L and M. The said valves are arranged for reciprocation, respectively, within valve-chambers c^{10} and c^{11} , formed within the casing C, and each valve preferably comprises a piston rod or stem and a couple of heads or disks mounted thereon. For example, the valve R may consist of a piston-rod r , provided with a couple of heads or disks r' r^2 , and the valve S may consist of a piston-rod s , provided with a couple of disks s' and s^2 . Extending transversely across and through the upper portion of the casing C is a duct or passage 21, which communicates at each end with the two valve-chambers c^{10} and c^{11} and which communicates at its middle portion with the pipe K. Steam entering the duct or passage 21 from the said pipe will be conducted by said duct to the two valve-chambers, and with the valves in the position shown in Figs. 9 95 and 10 will enter such chamber at points between the disks or heads of each valve—that is to say, steam entering the valve-chamber c^{10} will be received between the disks r' and r^2 , while the steam entering the valve-chamber c^{11} will be received between the disks s' and s^2 . From the space between the two disks r' and r^2 steam will pass by way of port 22 into both compartments of the low-pressure chamber, and at the same time therewith steam from the space between the disks s' and s^2 will pass by way of port 23 and also enter both compartments of the low-pressure piston-chamber. Steam entering the two compartments of the low-pressure 110 chamber by way of port 22 will expand between the piston projections and the abutments p p' , while the steam entering by way of the duct 23 will expand between the piston projections and the abutments o o' . By 115 such expansion on the part of the steam the piston will be rotated in the direction indicated by the arrow, and as the pistons D and N are both keyed to the shaft G the two pistons will therefore rotate in unison and maintain their relative positions. With steam entering and driving the pistons in the direction indicated the exhaust from the low-pressure chamber will take place through ports 24 and 25. Exhaust-steam entering the 120 port 24 will be conducted to one end of the valve-chamber c^{11} , while the exhaust escaping by way of port 25 will be received by one end portion of the valve-chamber c^{10} . (See 125

Figs. 9 and 10.) Extending longitudinally above the valves and through the casing are a couple of ducts or passages 26 and 27, connected by a transverse duct or passage 28.

5 The duct or passage 26 serves as a medium of communication between the opposite end portions of the valve-chamber c^{10} , and the duct or passage 27 serves in a like manner to connect the opposite ends of the valve-chamber c^{11} . Exhaust entering the valve-chamber c^{10} by way of duct 25 will pass into duct 26 and escape therefrom by way of duct 28 and pipe Q, while exhaust entering the valve-chamber c^{11} by way of duct 24 will pass into 15 duct 27, and from the latter also escape by way of duct 28 and pipe Q.

The ducts 26 and 27, while serving principally as a means of exhaust, also serve to balance the two reversing-valves by permitting exhaust-steam to pass to the opposite ends of the valve-chambers, so as to exert a like pressure upon each end of the inclosed valve. The steam-pressure between the disks of each valve is of course balanced at 25 all times, and by thus balancing the pressure of the exhaust the reversing-valves are easily and readily shifted when a reversal of the engine is desired. A reverse order of admission and exhaust to and from the low-pressure 30 cylinder and a consequent rotation of the pistons in a reverse direction from that indicated is obtained by shifting or reciprocating the valves R and S to the opposite ends of their respective valve-chambers. By thus 35 shifting the said reversing-valves to the opposite ends of their respective valve-chambers steam will then be admitted to the low-pressure chamber by way of ducts 24 and 25 and exhausted therefrom by way of ducts 22 and 23, for it will be observed that by such 40 shifting of the valves the space between disks s' and s^2 will then serve to connect duct 24 with one end of duct 21, so as to admit steam to the low-pressure chamber by way of the former, and also that the space between 45 disks r' and r^2 will, in a similar manner and for a like purpose, serve to connect duct 25 with the other end of duct 21. In such case steam entering the space between the disks 50 of valve S by way of duct 21 will pass from said space into duct 24, and from the latter will then enter the low-pressure chamber at a point immediately below the abutments o and o' , and steam entering the space between 55 the disks of valve R, also by way of the said duct 21, will pass into duct 25 and from the latter will then enter the low-pressure chamber at a point immediately above the abutments p and p' . With steam thus entering the low-pressure chamber the ports or ducts 22 and 23 will, as previously stated, then serve as exhaust ports or passages, as steam entering the low-pressure chamber by way of port or duct will exhaust by way of port or duct 22, 60 65 while steam entering by way of port or duct 25 will exhaust by way of port or duct 23, for with the valves so shifted the space be-

tween the disk r^2 and the end wall of valve-chamber c^{10} will serve to connect duct 22 with duct 26, while the space between disk s^2 70 and the end wall of the valve-chamber c^{11} will serve to connect duct 23 with duct 27, and from said ducts 26 and 27 the exhaust-steam will then finally escape by way of duct 28 and pipe Q. 75

The reversing-valves may be operated in any suitable manner; but as a matter of further improvement I prefer to connect all of the valves for simultaneous shift or adjustment, so as to simultaneously reverse the order of admission and exhaust in all of the piston-chambers. As a simple and effective arrangement for so doing I provide a rock-shaft T, mounted in suitable bearings t . The said shaft is preferably arranged between 85 the casings B and C, so as to extend transversely above the shaft G, and the bearings t may be conveniently mounted upon the bearings a^7 and a^9 . (See Figs. 1, 2, and 3.) The upwardly-extending crank-arms t' and t^2 and t^3 t^4 , with which the rock-shaft is provided, are adapted for connection with the four reversing-valves, and the hand-lever t^5 , secured to one end of the said shaft, is designed to afford a means for rocking or oscillating the latter for the purpose of shifting the said valves. The crank-arms t' and t^2 are connected by means of links t^6 with the ends of the piston-rods s and r , respectively, and the crank-arms t^3 and t^4 are similarly and respectively 100 connected with the ends of piston-rods l and m . With such provision and arrangement the four reversing-valves may be simultaneously shifted, so as to simultaneously reverse the order of admission and exhaust in 105 the three piston-chambers, it being observed that the valves are simultaneously shifted in the same direction. A rotary engine thus constructed is easily and quickly reversed, there being practically no steam-pressure to 110 overcome in shifting the valves and the extent of throw necessary on the part of the hand-lever being comparatively small. 115

As a matter of further and special improvement and with a view to affording means for increasing the power of the engine in case of a heavy load, provision is made for the admission of live steam directly to the low-pressure piston-chamber, whereby the latter may at any time be made to serve as a high-pressure chamber. As a simple and effective arrangement for so operating the engine when desired, I provide a by-pass 29, which serves to connect the primary inlet-pipe J with the pipe K. The by-pass is preferably controlled 120 by a suitable valve 30, and by operating the latter live steam may be admitted from the pipe J directly to the low-pressure chamber, in which case the latter will then serve as a high-pressure cylinder. 125 130

What I claim as my invention is—

1. A compound rotary engine comprising a casing and cylindric piston which rotates concentrically with said casing and which is pro-

vided with a plurality of annular flanges which divide the interior of the casing into a plurality of annular compartments or piston-chambers, each compartment being provided 5 with a plurality of piston projections which alternate with those of the adjacent or next compartment; and rotary abutments arranged at opposite sides of the piston, and which are of a diameter to extend and rotate between 10 the flanges of the latter, and which are provided with a plurality of peripheral notches or cavities adapted to receive the projections on the piston during the rotation of the latter; the said casing being provided with suitable 15 ports or passages for admitting and exhausting steam from one compartment to another, the said passages or ports being arranged so as to admit the steam at opposite or substantially opposite points for the purpose of balancing the pressure upon the piston, and such casing being also provided with suitable steam spaces or cavities for maintaining pressure upon the said rotary abutments, substantially as and for the purpose described.

25 2. A compound rotary engine comprising a suitable cylinder or casing, an annular cylindric or drum-like piston which rotates concentrically within said casing and which is peripherally flanged intermediate of its ends 30 in such manner as to divide the interior of the casing into a plurality of annular compartments, each compartment being provided with a plurality of projections and the projections of one compartment alternating with 35 those of the adjacent or next compartment; one or more rotary abutments provided with peripheral notches adapted to receive the said projections on the rotary piston and arranged to coöperate with said piston; and suitable 40 ports or passages whereby the steam may be admitted and exhausted from one compartment of the piston-chamber to another.

3. A compound rotary engine, comprising a suitable cylinder or casing, a cylindric piston 45 which rotates concentrically within said casing and which is provided with a peripheral flange at a point intermediate of its ends, the said flange serving to divide the interior of the casing into two compartments, a rotary 50 abutment for each compartment, a horse-shoe-shaped ring arranged between said abutments and opposite to or in line with said flange, and suitable ports or passages for admitting and exhausting the steam from one 55 compartment to another.

4. A compound multiple-expansion rotary engine, comprising high, intermediate and low pressure piston-chambers, the said chambers having suitable supply and exhaust 60 ports; concentric rotary pistons mounted to rotate in unison upon a shaft and inclosed and operating within said piston-chambers, the piston D being provided with end flanges d', d^2 and also with a flange d which is arranged adjacent to the flange d' , for the purpose stated; rotary abutments coöperating with said pistons; the steam being primarily

admitted to the high-pressure chamber wherein it operates to revolve the inclosed piston without expanding; the exhaust from the 70 said high-pressure chamber being received and expanded within the intermediate-pressure chamber, and the exhaust from the latter being received and expanded within the low-pressure chamber.

5. A compound multiple-expansion rotary engine comprising high, intermediate and low pressure piston-chambers; said chambers having suitable supply and exhaust ports; rotary pistons D and N mounted to rotate in 80 unison upon a single shaft G and inclosed and operating within said piston-chambers and provided respectively with flanges d, d', d^2 and n, n', n^2 for the purpose described; suitable abutments coöperating with said pistons; 85 the steam being primarily admitted to the high-pressure chamber E and allowed to pass through the latter without expanding; the exhaust from the said high-pressure chamber being received by and expanded within the 90 intermediate-pressure chamber F and the exhaust from the latter being received by and expanded within the low-pressure chamber.

6. A compound rotary engine comprising high, intermediate and low pressure piston-chambers; pistons D and N rotating in unison upon a single shaft within said chambers and provided respectively with flanges d, d', d^2 and n, n', n^2 , substantially as and for the purpose set forth; and suitable inlet and outlet ports 100 for admitting and exhausting steam to and from the said chambers; and suitable abutments coöperating with said pistons; the steam being primarily admitted to the high-pressure chamber and exhausted therefrom 105 to the intermediate-pressure chamber or chambers, and the exhaust from the latter being conveyed to the low-pressure chamber; and the said low-pressure chamber being provided with one or more live-steam openings, 110 whereby the pressure in such chamber may be augmented by a direct admission of steam at full boiler-pressure, and whereby said chamber may be made to serve as a high-pressure chamber.

115 7. A compound rotary engine comprising in combination the casing B providing a piston-chamber; a piston D rotating concentrically within said chamber and provided with one or more piston projections and also 120 with flanges d, d', d^2 for the purpose set forth; a cylindric rotary abutment provided with one or more recesses adapted to receive the said piston projection or projections during the rotation of the piston; and suitable 125 inlet and outlet ports for admitting and exhausting steam to and from the said piston-chamber.

8. A compound double-expansion rotary engine, comprising high, intermediate and 130 low pressure piston-chambers; rotary pistons inclosed within the said chambers and rotating in unison upon a single shaft; suitable abutments coöperating with said pistons;

suitable inlet and outlet ports for admitting and exhausting the steam to and from the said chambers; an inlet-pipe leading to the high-pressure chamber; an exhaust-pipe leading from the intermediate-pressure chamber to the low-pressure chamber; and a valve-controlled by-pass 29 leading from the said inlet-pipe to the said exhaust-pipe, whereby the said low-pressure chamber may be made 5 to serve as a high-pressure chamber; the steam being primarily admitted to the high-pressure chamber wherein it operates to rotate the inclosed piston without expanding, the exhaust from the high-pressure chamber 10 being received and expanded within the intermediate-pressure chamber, and the exhaust from the latter being received and expanded within the low-pressure chamber.

9. A rotary engine comprising in combination the casing C providing a piston-chamber; the piston N provided with flanges $n n' n^2$ and rotating concentrically within said chamber and provided with eight piston projections; a couple of cylindric rotary abutments located 15 at opposite sides of the said piston, each abutment being provided with a couple of recesses adapted to receive the said piston projections during the rotation of the piston; the said abutments having a rolling or frictionless 20 contact with the said piston; and the said casing being provided with suitable inlet and outlet ports for admitting and exhausting the steam to and from the said piston-chamber.

10. A reversible rotary engine comprising in combination the casing C adapted to provide a piston-chamber; a piston N provided with flanges $n n' n^2$ and rotating concentrically within said chamber and provided with one or more piston projections, such as shown; 35 one or more rotary abutments provided with recesses adapted to receive the said piston projection or projections; the abutment shaft or shafts being gear-connected with the piston-shaft; and one or more piston-valves for 40 controlling the supply and exhaust ports, whereby the engine may be reversed at will.

11. A compound double-expansion reversible rotary engine, comprising in combination high, intermediate and low pressure piston-chambers; the rotary flanged pistons D and N inclosed within said chambers and constructed substantially as shown and described; suitable abutments co-operating with said pistons; suitable supply and exhaust ports for 50 the piston-chambers, the steam being primarily admitted to the high-pressure chamber E wherein it operates to rotate the inclosed piston without expanding; the exhaust from said high-pressure chamber being received 55 and expanded within the intermediate-pressure chamber F, which is larger than said high-pressure chamber, and the exhaust from the chamber F being received and expanded within the low-pressure chamber; suitable 60 valves for controlling the said supply and exhaust ports; and means for operating said valves for the purpose of reversing the engine.

12. A compound reversible rotary engine, comprising the two cylinder-casings and pistons rotating therein; rotary abutments arranged at either side of each piston; a valve-chamber adjacent to each abutment-chamber; a reciprocating piston-valve in each valve-chamber; the casing having suitable ports or ducts which serve to connect the 70 valve-chamber with the piston-chamber at opposite points so as to balance the pressure upon the pistons; a rock-shaft provided with crank-arms having suitable connection with the rods or stems of the four piston-valves, 75 and a hand-lever for rocking the said shaft.

13. In a reversible rotary engine, the casing inclosing a rotary piston; the rotary abutments co-operating with said piston; the casing having suitable ports for admitting and 80 exhausting steam to and from the piston-chamber; a couple of reciprocating piston-valves for controlling said ports; a rock-shaft provided with crank-arms, links for connecting the said arms with the stems or rods of the 85 said valves, and a hand-lever for rocking said shaft.

14. A reversible rotary engine comprising a casing providing a piston-chamber; a piston rotating therein; one or more abutments 95 co-operating with said piston; the casing having suitable ports for admitting and exhausting steam to and from the said piston-chamber, the steam being admitted at opposite sides of the piston so as to balance the pressure upon the latter; a couple of reciprocating piston-valves for controlling the said ports; a rock-shaft having suitable connection with the stems or rods of said valves; and means for rocking said shaft for the purpose of 100 shifting the valves and thereby reversing the engine.

15. A compound double-expansion rotary engine, comprising a couple of rotary pistons mounted to rotate in unison upon a rotary 110 shaft, a couple of cylinder-casings inclosing the said pistons, one of said pistons being flanged so as to divide the interior of the casing into high and intermediate pressure piston-chambers, and the other of the said two 115 cylinder-casings being adapted to provide a low-pressure piston-chamber; rotary abutments arranged at each side of the said pistons and provided with recesses adapted to receive the piston projections, suitable inlet 120 and exhaust ports for admitting and exhausting the steam to and from the piston-chambers, the steam being admitted to each piston-chamber at opposite points so as to balance the pressure upon the rotary pistons, 125 and the steam being primarily admitted to the high-pressure chamber wherein it operates to rotate the inclosed piston without expanding; the exhaust from the said high-pressure chamber being received and expanded with 130 in the intermediate-pressure chamber, and the exhaust from the latter being received and finally expanded within the low-pressure chamber.

16. A compound double-expansion rotary engine, comprising a couple of cylindric or drum-like rotary pistons keyed to a rotary shaft and arranged to rotate within a couple 5 of cylinder-casings, one of said pistons being flanged so as to divide the interior of the casing into high and intermediate pressure piston-chambers; rotary abutments coöperating with said pistons and arranged in the same 10 plane as the piston-shaft, said abutments being recessed so as to permit the piston projections to pass, suitable supply and exhaust ports for admitting and exhausting the steam to and from the piston-chambers, the steam 15 being admitted to each piston-chamber at opposite points so as to balance the pressure upon the inclosed pistons, and the steam being primarily admitted to the high-pressure compartment wherein it operates to rotate the 20 inclosed piston without expanding; the exhaust from the said high-pressure chamber being received and expanded within the intermediate-pressure chamber, and the exhaust from the latter being received and finally ex- 25 panded within the low-pressure chamber; and the said piston-shaft being gear-connected with the said rotary abutments whereby the latter will have a rolling contact with the former.

17. A compound double-expansion rotary engine, comprising a couple of cylindric or drum-like rotary pistons mounted to rotate in unison upon a horizontal rotary shaft, a casing inclosing each piston, one of said pistons 30 being flanged so as to divide the interior of one casing into high and intermediate pressure piston-chambers, rotary abutments arranged at each side of the said pistons and in the same plane as the piston-shaft, horseshoe- 35 shaped rings arranged upon the abutment-shafts opposite to the piston-flanges, steam-spaces back of the abutments and rings for the purpose of keeping the said abutments in contact with the pistons, the said abut- 40 ments being provided with notches or recesses adapted to receive the piston projections during the rotation of the pistons, and the said abutments being gear-connected with the piston-shaft whereby the former will have a roll- 45 ing contact with the said piston; suitable supply and exhaust ports for admitting and exhausting steam to and from the piston-chambers, the steam being admitted at opposite points so as to balance the pressure upon the 50 pistons, and the steam being primarily admitted to the high-pressure chamber wherein it operates to rotate the inclosed piston without expanding; the exhaust from the said high-pressure chamber being received and 55 expanded within the intermediate-pressure chamber, and the exhaust from the latter being received and expanded within the low-pressure chamber.

18. In a rotary engine, a casing adapted to 60 provide a piston-chamber, a cylindric or drum-like piston rotating within said chamber and

provided with one or more piston projections, and the said piston being also provided with a flange which serves to divide the piston-chamber into two compartments; one or more 70 rotary abutments provided with one or more recesses or notches adapted to receive the said piston projection or projections, the said abutment or abutments having a rolling contact with the said piston, and one or more 75 horseshoe-shaped rings loosely mounted upon the abutment shaft or shafts and arranged opposite the said piston-flange; and the said casing being provided with suitable inlet and outlet ports for admitting and exhausting the 80 steam to and from the piston-chamber, and said casing being also provided with one or more pressure spaces or cavities for balancing the pressure upon the said abutment or abutments and keeping the latter in contact 85 with the said piston.

19. In a rotary engine, a casing adapted to provide a piston-chamber, a cylindric or drum-like piston rotating concentrically within said chamber and provided with four oppositely-arranged piston projections, the said piston being also provided with three peripheral flanges which serve to divide the piston-chamber into two compartments; a couple of rotary shafts arranged at opposite sides of the 90 piston and gear-connected with the piston-shaft, two rotary abutments keyed to each of said rotary shafts, the two abutments on one shaft being arranged to project respectively within one and the other of the said two compartments at one side of the piston, and the two abutments on the other shaft being arranged in a similar manner on the opposite side of the said piston; each abutment being provided with a couple of recesses adapted to 100 receive the said piston projections, and the said abutments having a rolling contact with the piston; three horseshoe-shaped rings loosely mounted upon each abutment-shaft, the said rings being arranged opposite the 105 piston-flanges, and the cylinder-casing being provided with pressure chambers or cavities whereby the said abutments are kept in contact with the rotary piston.

20. In a compound rotary engine, a cylinder-casing and a piston rotating concentrically therein, the said piston being flanged so as to divide the interior of the casing into two compartments, and the said piston being also provided with piston projections whereof those of one compartment alternate with those of the other compartment; two or more rotary abutments provided with recesses adapted to receive the said piston projections during the rotation of the piston, one or more 115 horseshoe-shaped rings arranged upon the abutment shaft or shafts opposite the piston flange or flanges, and one or more pressure spaces or cavities for keeping the said abutments in contact with the piston; one or more 120 inlet-ports for admitting steam to one of said two compartments, ports or ducts for convey- 125 130

ing the exhaust from such compartment to the other compartment, and suitable ports or ducts for exhausting from the latter.

21. In a compound rotary engine, a cylinder-casing and a piston rotating concentrically therein; the said piston being flanged so as to divide the interior of the casing into two compartments, and the piston being also provided with piston projections, preferably four in each compartment, and those of one compartment alternating with those of the other compartment; a couple of rotary shafts arranged at opposite sides of the piston and gear-connected with the piston-shaft, two cylindric abutments keyed to each rotary shaft in such manner as to provide each compartment with two oppositely-arranged rotary abutments, and horseshoe-shaped rings loosely mounted upon the abutment-shafts and arranged opposite the piston flange or flanges, the cylinder-casing being provided with pressure spaces or cavities for keeping the abutments in contact with the piston; and the said casing being also provided with ducts or ports whereby the steam will be primarily admitted to one of said compartments wherein it will operate to rotate the inclosed piston without expanding, and whereby the exhaust from such compartment will be received and expanded within the other of the said two compartments.

22. In a reversible rotary engine, a casing adapted to provide a piston-chamber, a cylindric or drum-like piston rotating concentrically within the said chamber and provided with a plurality of piston projections, a couple of abutments arranged at either side of the said piston and provided with recesses adapted to receive the said piston projections, the said abutments being gear-connected with the piston-shaft, and the said casing being provided with suitable inlet and outlet ports for admitting and exhausting steam to and from the piston-chamber, the steam being admitted at opposite points so as to balance the pressure upon the piston; a couple of piston-valves arranged for reciprocation in suitable valve-chambers and adapted to control the admission and exhaust ports, and means for operating said valves whereby the engine may be reversed at will.

23. In a reversible rotary engine, a casing adapted to provide a piston-chamber, a cylindric piston rotating concentrically in said chamber and provided with piston projections, rotary abutments arranged at either side of the piston and provided with recesses adapted to receive the piston projections, a couple of valve-chambers formed within the cylinder-casing, each valve-chamber having one or more ports leading to and communicating with the piston-chamber at a point immediately above the adjacent abutment, and each valve-chamber having one or more ports leading to and communicating with the piston-chamber at a point immediately below the said abutment; the opposite ends of each

valve-chamber being connected by means of one or more ports or ducts, and each valve-chamber being provided with supply and exhaust ports or ducts; a piston-valve in each valve-chamber adapted to control the said ports or ducts, and means for shifting or reciprocating said valves for the purpose of reversing the engine.

24. In a reversible rotary engine, a casing adapted to provide a piston-chamber, a cylindric piston rotating concentrically therein and provided with piston projections, rotary abutments arranged at either side of the piston and provided with recesses adapted to receive the piston projections, a valve-chamber formed in the casing above each abutment, a duct or passage above each valve-chamber serving to connect the opposite ends of such chamber, an exhaust duct or passage connecting the said valve-chambers, a supply duct or passage also connecting the two valve-chambers, an inlet for the said supply-duct and an outlet for the said exhaust-duct, one or more ports or ducts leading from each valve-chamber to and communicating with the piston-chamber at a point immediately above the adjacent abutment, and one or more ducts or ports leading from each valve-chamber to and communicating with the piston-chamber at a point immediately below the adjacent abutment; a piston-valve in each valve-chamber, and means for shifting the said valves for the purpose of reversing the engine.

25. In a compound reversible rotary engine, a cylinder-casing and a piston rotating concentrically therein; the said piston being flanged so as to divide the interior of the casing into two compartments, and being also provided with a plurality of piston projections whereof those of one compartment alternate with those of the other compartment; a couple of rotary abutments arranged at opposite sides of the piston and having recesses adapted to receive the piston projections; suitable ports for admitting and exhausting steam to and from one of said compartments, suitable ports for conveying such exhaust to the other compartment, exhaust-ports for the latter, a couple of piston-valves for the purpose of reversing the engine.

26. In a compound reversible rotary engine, a cylinder-casing and a piston rotating concentrically therein; the said piston being flanged so as to divide the interior of the casing into two compartments, and being also provided with a plurality of piston projections whereof those of one compartment alternate with those of the other compartment; rotary abutments arranged at either side of said piston and having recesses adapted to receive the piston projections, a valve-chamber adjacent to each abutment, and a duct or passage connecting the opposite ends of each valve-chamber; each valve-chamber having a couple of ports leading to and opening into the two compartments at points immediately

above the adjacent abutment, and each valve-chamber having a couple of ports or ducts leading to and opening into the said two compartments at points immediately below the adjacent abutment; an admission-port for each valve-chamber, and an exhaust-port for each valve-chamber; a piston-valve inclosed within each valve-chamber, each valve consisting of a piston-rod with a plurality of disks or heads, and means for shifting the valves for the purpose of reversing the engine; the steam being primarily admitted to one compartment wherein it operates to rotate the inclosed piston without expanding, and the exhaust from such compartment being received and expanded within the other of the said two compartments.

27. A compound double-expansion rotary engine, comprising high, intermediate and low pressure piston-chambers, pistons rotating concentrically within said chambers, rotary abutments coöperating with said pistons, a plurality of valve-chambers having ports or ducts leading to and communicating with the piston-chambers, piston-valves in said valve-chambers adapted to control the admission and exhaust of steam to and from the piston-chambers, ports or ducts for primarily admitting steam to such valve-chambers, and ports or ducts for permitting the exhaust to escape from said valve-chambers; the steam being primarily admitted to the high-pressure chamber wherein it operates to rotate the inclosed piston without expanding, the exhaust from said high-pressure chamber being received and expanded within the intermediate-pressure chamber, and the exhaust from the latter being received and expanded within the low-pressure chamber; and means for simultaneously shifting the said valves for the purpose of reversing the order of admission and exhaust to and from the piston-chamber, whereby the engine may be reversed at will.

45 28. A compound double-expansion reversible rotary engine, comprising high, intermediate and low pressure piston-chambers, pistons rotating concentrically within said chambers, rotary abutments coöperating with said pistons, a couple of valve-chambers adjacent to the high and intermediate pressure chambers and having suitable ports or ducts leading to the said piston-chambers, and a three-disked piston-valve in each valve-chamber; a couple of valve-chambers adjacent to the low-pressure chamber and having suitable ports or ducts leading to the latter, and a two-disked piston-valve in each of said valve-chambers; the steam being first admitted to the valve-chambers adjacent to the high and intermediate pressure chambers, and from the latter admitted to the high-pressure chamber wherein it operates to rotate the inclosed piston without expanding; the exhaust from the high-pressure chamber being allowed to escape back into the said adjacent valve-chambers, and from the latter permitted to

pass into and expand within the intermediate-pressure chamber; the exhaust from the low-pressure chamber being also conducted back to the adjacent valve-chambers, and from the latter allowed to escape into the valve-chambers adjacent to the low-pressure chamber, the steam thus entering the valve-chambers adjacent to the low-pressure chamber being then received and expanded within the said low-pressure chamber, the exhaust from the latter being then conducted back to such adjacent valve-chambers, and from the latter permitted to escape from the engine; and means for simultaneously shifting the said reversing-valves for the purpose of reversing the engine.

29. In a reversible rotary engine, a casing adapted to provide a piston-chamber, a piston rotating therein, a couple of oppositely-arranged abutments coöperating with said piston, the casing being provided with ports or ducts for admitting and exhausting steam to and from the said piston-chamber, the steam being admitted at opposite points so as to balance the pressure upon the piston, a couple of reciprocating piston-valves adapted to control the said ports, a rock-shaft provided with crank-arms having suitable connection with the stems or rods of said valves, and a hand-lever for rocking said shaft for the purpose of reversing the engine.

30. A compound reversible rotary engine, comprising the two cylinder-casings and pistons rotating therein; suitable abutments coöperating with said pistons, the casings being provided with suitable ports for admitting and exhausting steam to and from the piston-chambers, piston-valves adapted to control the said ports; a rock-shaft provided with crank-arms having suitable connection with the stems or rods of said valves, and means for rocking said shaft for the purpose of reversing the order of admission and exhaust and thereby reversing the engine.

31. In a reversible rotary engine, a casing providing a piston-chamber, a piston rotating concentrically within said piston-chamber and provided with piston projections, rotary abutments arranged at either side of the piston and provided with recesses adapted to receive the said piston projections, a couple of valve-chambers each provided with a port leading to and opening into the piston-chamber at a point immediately above the adjacent abutment, and each valve-chamber having a port leading to and opening into the piston-chamber at a point immediately below the adjacent abutment; a two-disked piston-valve in each valve-chamber, a balancing port or duct for connecting the opposite ends of each valve-chamber, a port or duct connecting one valve-chamber with the other valve-chamber, a port or duct connecting the balancing port or duct of one valve-chamber with the balancing port or duct of the other valve-chamber, a supply-passage opening into the duct which serves to connect the two valve-chambers, an ex-

haust-passage leading from the duct which serves to connect the two balancing ports or ducts, and means for shifting the said valves for the purpose of reversing the engine.

5 32. In a compound reversible rotary engine comprising a plurality of piston-chambers, a reversing-valve chamber having its end portions connected by a duct or passage and provided with supply and exhaust ports; the 10 said valve-chamber having a pair of ports or ducts leading to one piston-chamber, and having also a pair of ducts or ports leading to the next or adjacent piston-chamber; a three-disked reciprocating piston-valve inclosed in 15 said valve-chamber and adapted to control the said ports, and means for shifting the said valve for the purpose of reversing the engine.

33. A compound double-expansion rotary 20 engine, comprising high, intermediate and low pressure piston-chambers, pistons rotating concentrically within said chambers and provided with piston projections, the piston 25 projections in the high-pressure chamber alternating with those in the intermediate-pressure chamber, and the piston projections in the latter chamber alternating with those of the low-pressure chamber; rotary abutments 30 provided with recesses adapted to receive the said piston projections, suitable supply and exhaust ports for admitting and exhausting steam to and from the said piston-chambers, the steam being admitted to each chamber at opposite points so as to balance the pressure 35 upon the inclosed piston; and the steam being primarily admitted to the high-pressure chamber wherein it operates to rotate the inclosed piston without expanding, the exhaust from the high-pressure chamber being received and expanded within the intermediate-pressure chamber, and the exhaust from the latter being received and expanded within the low-pressure chamber.

34. A compound double-expansion rotary 45 engine, comprising the high, intermediate and low pressure piston-chambers, pistons rotating concentrically therein and provided with piston 50 projections, four of such projections in each chamber, the piston projections of the high-pressure chamber alternating with those of the intermediate-pressure chamber, and the piston projections of the latter alternating with those of the low-pressure chamber; rotary abutments arranged at either side of 55 said pistons and provided with recesses adapted to receive the said piston projections, inlet and outlet ports adjacent to said abut-

ments for admitting and exhausting steam to and from the said chambers, the steam being admitted at opposite points so as to balance 60 the pressure upon the pistons; and the steam being primarily admitted to the high-pressure chamber wherein it operates to rotate the inclosed piston without expanding, the exhaust from the high-pressure chamber being received and expanded within the intermediate-pressure chamber, and the exhaust from the latter being received and expanded within the low-pressure chamber.

35. A compound double-expansion rotary 70 engine, comprising two cylinder-casings, a cylindric piston rotating concentrically within each casing, each piston being provided with three flanges serving to divide the interior of each casing into two compartments, 75 the two compartments in one casing serving as high and intermediate pressure chambers, and the compartments in the other chamber combining to serve as a low-pressure chamber; rotary abutments arranged at either side 80 of said pistons and provided with recesses adapted to receive the piston projections, the piston projections of the high-pressure chamber alternating with those of the intermediate-pressure chamber, and those of the latter 85 alternating with those of the low-pressure chamber; three or more horseshoe-shaped rings loosely mounted upon each abutment-shaft opposite to the piston-flanges, steam spaces or cavities back of the abutments and 90 rings, pressure being maintained in such spaces or cavities by the steam carried in the abutment-recesses, and such pressure serving to balance the pressure upon the said abutments and rings and also to keep the former in contact with the pistons; the said casing being provided with suitable ports for admitting and exhausting steam to and from the said piston-chambers, such admission being at opposite points so as to balance the 95 pressure upon the pistons; the steam being primarily admitted to the high-pressure chamber wherein it operates to rotate the inclosed piston without expanding, the exhaust from the high-pressure chamber being received and 100 expanded within the intermediate-pressure chamber, and the exhaust from the latter being received and expanded within the low-pressure chamber.
